United States Patent Office

Des. 206,944
Patented Feb. 14, 1967

206,944

COMBINED FOOD MIXER AND CAN OPENER OR THE LIKE

Douglas N. Cabell, Bloomfield Hills, Mich., assignor to Ronson Corporation, Woodbridge, N.J., a corporation of New Jersey

Filed Feb. 28, 1966, Ser. No. 1,217

Term of patent 14 years

(Cl. D44—1)

FIG. 1 is a side elevational view of a combined food mixer and can opener or the like showing my new design; FIG. 2 is a top plan view thereof;

FIG. 3 is a front elevational view thereof;

FIG. 5 is a bottom plan view thereof;

FIG. 6 is a rear elevational view thereof.

I claim:

The ornamental design for a combined food mixer and can opener or the like, as shown.
